BATHTUB ADAPTING MEANS

George Sakier, New York, N. Y., assignor to The Accessories Company, Inc., New York, N. Y., a corporation of Delaware

Application February 5, 1934, Serial No. 709,700

12 Claims. (Cl. 4—173)

My invention relates to improvements in bath room furnishings and the same has for its object the provision of simple, efficient and inexpensive means whereby bath rooms equipped with old forms of bath tubs may be readily and conveniently modernized.

Further, said invention has for its object to provide means whereby it becomes possible to remove an old style or form of bath tub supported on legs or feet and replace the same with a bath tub of the "apron" type, without necessitating the tearing out of the old piping, and damaging the walls, floors, etc. of the bath room.

Further, said invention has for its object to provide an adapting member or element in the form of a relatively shallow panel or casing which may be readily interposed between the rear and side edges of the bath tub, and the walls of the room adjacent thereto, and in which said panel or casing serves to receive and conceal the necessary piping.

Further, said invention has for its object to provide an adapting member or element for the purposes specified whose front wall portion serves to accommodate the necessary valves, spout, grab bar, soap and sponge receptacles, and whose upper portion may serve as a shelf or support for bottles and other toilet articles or containers.

Further, said invention has for its object to provide a construction of the character specified providing a fluid-tight joint between the upper rear and side edges of the bath tub and the adapting member.

Other objects will in part be obvious and in part be hereinafter described.

To the attainment of the aforesaid objects and ends my invention consists in the novel features of construction, and in the combination, connection and arrangement of parts hereinafter more fully described and then pointed out in the claims.

In the accompanying drawings:—

Figure 1 is a perspective view showing a portion of a bath room and corner tub, and one form of adapting means, constructed according to and embodying my said invention applied thereto;

Fig. 2 is a plan or top view;

Fig. 3 is an enlarged detail front view, partly broken away and in section;

Fig. 4 is an enlarged vertical section, slightly in perspective, on the line 4—4 of Fig. 2, showing the construction of the adapting member, and the securing means associated therewith, and

Fig. 5 is a similar view illustrating a modification, as seen from the rear of the tub.

In said drawings 10 designates a corner bath tub of the well-known "apron" type comprising a receptacle portion 11, and front and end apron portions 12 and 13, respectively. The tub 10 is provided along its rear upper edge, and its right-hand vertical edge with an enlarged rearwardly extending rim portion 14.

15 denotes an adapting member in the form of a panel or hollow casing including a top 16, from whose forward edge depends a vertical front 10 wall 17, and from whose rear edge depends a short, longitudinal flange 18. The said adapting member is preferably made of sheet metal, and enameled, coated or otherwise decorated, as desired, and is supported in position with its flange 15 portion 18 in engagement with the wall 19 of the room, or other rigid vertical support.

23 denotes a relatively-narrow longitudinal strip or plate of metal or other suitable material which is secured horizontally adjacent to its upper and lower edges to a wall, studs or other vertical support by screws or nails 24. The said strip or plate is provided along its upper edge with an offset flange 25 to provide a longitudinal recess between its rear surface and the surface 23 of the adjacent wall which longitudinal recess is adapted to receive the depending flange 18 of the adapting member 15 whereby to support said adapting member and hold the upper rear edge thereof in close engagement with the wall.

26 denotes a sheet metal angular member comprising a flat, horizontal intermediate portion 27 having an upwardly-extending flange 28 along its rear edge, and a depending substantially V-shape portion 29 along its forward edge. The said member 26 is secured to the flange 14 along the rear edge of the tub and to the strip or plate 23 by one or more clamping members 30. Each clamping member 30 comprises a vertical wall portion 31 having a short, forwardly extending flange 31a along its upper edge, and an upwardly and forwardly-inclined flange 31b along its lower edge. The flange 31a serves as a finger piece or grip to facilitate the drawing up of the clamp to bring the inclined flange 31b into engagement with the underside of the rim 14 of the tub preparatory to securing the parts together by the screws 32. The flanges 31a and 31b are adapted to receive between the same the enlarged portion of the rim 14 of the tub, and be clamped in position by means of screw 32 which extends through slots in the flange 28 and the wall portion 31 of the clamping member 30, and into the strip or plate 23.

55

33 denotes a finishing strip or molding having rear and bottom sides 34, 35, respectively, arranged at right angles to each other, and a rounded or other form of outer face 36. The strip 33 is preferably formed of pliable metal, such as white metal or any suitable alloy which is pliable, to permit of its being shaped to the contour of the tub, and is provided with a longitudinal slot 34a which extends inwardly at an angle 10 of approximately 45° from the junction of its side and bottom to receive the forward free edge of the V-shape portion 29 of the member 26. The forward edge of said V-shape portion may be fluted, serrated or otherwise treated to 15 insure a firm anchorage when the edges of said strip 33 at each side of the slot 34 are pressed together and into engagement with the free edge of said V-shape portion 29. One strip 33 may extend longitudinally across the back of the tub and 20 down along its exposed end, and a separate strip 33 extend along the top and front edges of the left-hand end of the top of the tub.

When the finishing strip or moulding 33 is duly secured to the clamped edge of the member 29, a 25 horizontal space or recess will be provided between the vertical rear side of said strip or moulding 33 and the vertically-extending portion of the V-shape member 29 to receive the lower edge of the wall portion 17 of the adapting member 15. The arrangement and relation of said recess and the lower edge of said wall portion 17 is such 30 that a limited vertical movement of the tub 10 and molding 33 secured thereto may take place, due to settling of the tub or the floor, without 35 causing the lower edge of said wall portion to become disengaged from said recess. The space between the rear of the V-shape portion 29 and the forwardly-inclined portion of the rim 14 may, when desired, be filled with a suitable cement 40 37.

The space within the hollow panel or casing 15 is designed to receive the water supply, waste and vent pipes, and the front wall of said panel or casing 15 is suitably apertured to permit of the 45 attachment of the bath tub fixtures, i. e., valves 41 and spout 42 to said pipes, and also to receive the soap receptacle 43 and the sponge receptacle 44, and the grab bar 45.

In the modification illustrated at Fig. 5, the 50 bath tub and the adapting means including the member 15, and the molding strip 33 are the same as in the main construction. The channel member 26a in the present construction has a downwardly extending flange 28a which engages 55 with the rear edges of the rim 14 of the tub, and is secured thereto at intervals by angular clamps 46 and screws 47. The upper portion of the adapting member 15 is secured in position by a vertical bracket 48 having a horizontal upper portion 49 engaging with the underside of the top 16 of the member 15. The portion 49 terminates in an offset end 50 secured to the wall by a screw or other fastening means extending 60 through the aperture 51 in said offset end. In the space provided by the offset end 50 the depending flange 18 at the upper rear edge of the top 16 is disposed, and the lower end of the bracket 48 which terminates in a foot 52 is secured 65 to the floor by a screw 53 passing through the same.

While I have shown the panels or casings 15 as 70 extending only a short distance above the top of the bath tub, it is to be noted that the same may extend upwardly to any height desired, even to

the extent of covering the entire wall space between the top of the tub and the ceiling of the room.

It is also to be noted that while I have shown the adapting members 15, and the connecting means therefor as applied to the back and one end of the tub, it will, of course, be understood that the same may be applied at all of the bounding edges of a tub, depending upon its construction, i. e., the number of sides or ends of the tub which are to remain exposed.

Having thus described my said invention, what I claim and desire to secure by Letters Patent is:

1. A bath tub adapter casing comprising a panel member adapted to be disposed along the edges 15 of the tub lying adjacent to the walls of a room, means for supporting said panel member, a member disposed along the edges of the tub contiguous to the inner edge of said panel member, and a finishing strip secured to said last-named member 20 and conforming to the contour of the tub.

2. A bath tub adapter casing comprising a panel member adapted to be disposed along the edges 25 of the tub lying adjacent to the walls of a room, means for supporting said panel member, a member disposed along the edges of the tub contiguous to the inner edge of said panel member, and a pliable finishing strip secured to said last-named member and conforming to the contour of the tub.

3. A bath tub adapter casing comprising a panel member adapted to be disposed along the edges 35 of the tub lying adjacent to the walls of a room, means for supporting said panel member, a member disposed along the edges of the tub contiguous to the inner edge of said panel member, and a finishing strip formed of pliable metal secured to said last-named member and conforming to the contour of the tub.

4. A bath tub adapter casing comprising a panel 40 member adapted to be disposed along the edges of the tub lying adjacent to the walls of a room, means for supporting said panel member, and anchoring member, clamping means for securing said anchoring member to the edge of the tub; 45 said anchoring member engaging the inner edge of said panel member and having a forwardly extending edge, and a finishing strip secured to the forward edge of said anchoring member and engaging the adjacent outer sides of said tub and 50 the front wall of said panel member.

5. A bath tub adapter casing comprising a panel member adapted to be disposed along the edges of the tub lying adjacent to the walls of a room, means for supporting said panel member, an anchoring member disposed along the edges of the tub contiguous to the inner edge of said panel member, means for securing said anchoring member to said tub and the wall, and a finishing strip secured to the edge of said anchoring member and engaging the outer sides of said tub and the front wall of said panel member.

6. A bath tub adapter casing comprising a hollow member having a tub-receiving cut-out 65 portion and adapted to be disposed along the edges of the tub lying adjacent to the walls of a room, a flanged member, an anchoring member engaging the edges of the tub and adapted to engage the inner edge of said hollow member, 70 said flanged member and said anchoring member receiving therebetween the edge of the tub, means for securing said flanged member and said anchoring member together, and a finishing strip having a longitudinal slot therein; the 75

- forward edge of said anchoring member extending into the slot in said finishing strip and engaging the outer sides of said tub and the front wall of said hollow member.
5. 7. A bath tub adapter casing comprising a hollow, sheet metal member adapted to be disposed along the edges of the tub lying adjacent to the walls of a room, a longitudinal plate secured to the wall for supporting the upper end 10 of said hollow member, an anchoring member engaging the upper side of the tub adjacent to the edges thereof and adapted to engage the inner edge of said hollow member, a flanged longitudinal member having its flange portion 15 engaging the underside of the tub along its said edge, means for securing said anchoring member and said flanged longitudinal member together and to said longitudinal plate, and a pliable, metal finishing strip having a longitudinal 20 slot; the forward edge of said anchoring member extending into and secured within the slot in said finishing strip, and the angular faces of said finishing strip engaging the outer sides of said tub and the front wall of said hollow member.
25. 8. A bath tub adapter casing comprising a hollow, sheet metal member adapted to be disposed along the edges of the tub lying adjacent to the walls of a room, a longitudinal plate secured to the wall having an offset upper edge 30 to secure and support the upper end of said member, an anchoring member engaging the upper side of the tub and adapted to engage the inner edge of said hollow member; said anchoring member having an upwardly extending 35 corrugated flange, and a pliable, transversely compressible metal finishing strip having a longitudinal slot; the forward corrugated edge of said anchoring member extending into the slot in said finishing strip, and the angular faces of said finishing strip engaging the upper side of said tub and the front wall of said hollow member, a longitudinal member having a forwardly and upwardly inclined flange along its 40 lower edge engaging the underside of the tub adjacent to the edges thereof, means for securing 45 said anchoring member and said longitudinal member together and to said longitudinal plate.
50. 9. A bath tub adapter casing comprising a hollow, sheet metal member including a top and a front wall and having a cut out portion to accommodate a bath tub, adapted to be disposed along the edges of the tub lying adjacent to the walls of a room, a longitudinal plate fixedly secured to the wall having an offset longitudinal upper edge to receive and support the upper end of said hollow member, horizontal and vertical anchoring members embracing the edges 55
- of the tub contiguous to the inner edge of said hollow member, means for securing the ends of said anchoring members together with their ends in spaced relation, means for securing said anchoring members to the edges of said tub, and a finishing strip having angular under and rear faces and a longitudinal slot extending diagonally into said strip; the forward edge of each anchoring member being corrugated and extending into the slot in said finishing strip, and the angular faces of said strip engaging the outer sides of said tub and the front wall of said hollow member.
5. 10. A bath tub adapter casing comprising a hollow, sheet metal member having a cut out 15 portion to accommodate a bath tub, adapted to be disposed along the edges of the tub lying adjacent to the walls of a room, brackets for supporting said hollow member, horizontal and vertical anchoring members embracing the edges 20 of the tub and adapted to engage the inner edge of said hollow member along said cut out portion, means for securing the ends of said anchoring members together with their ends in spaced relation, means for securing said anchoring members to the edges of said tub, and a finishing strip having angular under and rear faces and a longitudinal slot extending diagonally into said strip; the forward edge of each anchoring member extending into the slot in 30 said finishing strip, and the angular faces of said strip engaging the outer sides of said tub and the front wall of said member.
11. A device of the character described comprising an anchoring member adapted to engage 35 certain of the edges of a bath tub or analogous structure and having an outwardly directed flange, a panel member having the inner edge thereof engaging said anchoring member, and a finishing strip of pliable material having a longitudinal groove therein to receive said flange and capable of being compressed into firm engagement therewith and with the contiguous surfaces of the tub and panel member.
12. A device of the character described comprising a longitudinal anchoring member adapted to be engaged with the edge of a bath tub or analogous structure and having an angularly related edge portion forming a longitudinal recess therein, a panel member adapted to be secured to the contiguous wall portion and having the inner edge thereof extending into said recess, and a finishing strip of pliable material having a slit therein receiving said angularly related edge portion and a plurality of sides arranged at an angle to each other for engagement with the contiguous surfaces of the tub and panel member.

GEORGE SAKIER.
